UNITED STATES PATENT OFFICE.

GEORGE S. MAXWELL, OF JERSEY CITY, NEW JERSEY, ASSIGNOR OF ONE-HALF TO HENRY D. CRIPPEN, OF NEW YORK, N. Y.

DESIGN FOR A SUPPORT FOR PUNCHING-BAGS.

SPECIFICATION forming part of Design No. 35,678, dated February 4, 1902.

Application filed October 16, 1901. Serial No. 78,888. Term of patent 14 years.

To all whom it may concern:

Be it known that I, GEORGE S. MAXWELL, a citizen of the United States, residing at Jersey City, in the county of Hudson and State of New Jersey, have invented and produced a new and original Design for a Support for Punching-Bags, of which the following is a specification, reference being had to the accompanying drawings, forming a part thereof.

10 Figure 1 is a side elevation of a support or bracket, showing my new design. Fig. 2 is a plan looking from the top of Fig. 1. Fig. 3 is an end elevation showing the outline of the wall-plate.

15 As shown in the drawings, the leading or material features of my design consist of a plate A, having an arm B projecting therefrom, the end of which arm is curved or bent,

as shown at C, and carries a dome-shaped part E, having an aperture in the crown thereof, as indicated at D, and having the edge of its rim flanged or turned back to present an annular surface F.

Having described my invention, what I claim as new, and desire to secure by Letters Patent, is—

The design for a support for punching-bags, as herein shown and described.

In testimony whereof I have signed my name to this specification in the presence of two subscribing witnesses.

GEORGE S. MAXWELL.

Witnesses:

H. M. SEAMANS,
I. V. SCOTT.
